UNITED STATES PATENT OFFICE.

JOHAN H. E. THOMSEN, OF HOLLIS, NEW YORK.

AUTOMOBILE ACCESSORY.

1,333,516.

Specification of Letters Patent. Patented Mar. 9, 1920.

Application filed January 22, 1919. Serial No. 272,544.

To all whom it may concern:

Be it known that I, JOHAN H. E. THOMSEN, a citizen of the United States, residing at Hollis, in the county of Queens and State of New York, have invented certain new and useful Improvements in Automobile Accessories, of which the following is a specification.

This invention has relation to automobile accessories, and has for an object to provide a device which is to be supported upon the windshield to shade the eyes of the driver against strong light which may come from any source directly ahead.

Another object of the invention is to provide a device of this character in the nature of a support to be placed upon the upper edge of the windshield whereby it may be moved from one point to another, and a shade depending from the support, for the purpose set forth.

A still further object of the invention is to provide a device for the purpose mentioned which embodies a casing and a clamp to secure the same to a windshield, a curtain roller and shade inclosed within the casing, and a folding means to serve as a guide for the shade, to brace the same in any lowered position thereof and to prevent 30 flapping of the shade in the wind.

In addition to the foregoing, this invention comprehends improvements in the details of construction and arrangement of parts, to be hereinafter described and particularly set forth in the appended claims.

In the accompanying drawings in which similar and corresponding parts are designated by the same characters of reference throughout the several views in which they 40 appear,

Figure 1, is a view in perspective of my invention mounted upon a windshield.

Fig. 2 is a view of the device in front elevation with parts broken away, showing the 45 guides in folded position.

Fig. 3 is a view of the device in end elevation.

Fig. 4 is a view thereof in front elevation with the guides extended and the shade 50 partly lowered.

Fig. 5 is a view of the device in cross section.

Fig. 6 is a bottom plan view of the device, and

Fig. 7 is a detail section taken on the line 55 7-7 of Fig. 2.

With reference to the drawings, 10 indicates a semi-cylindrical casing, closed at its ends and formed in its under side with a longitudinally extending slot 11. Brackets 12 are secured interiorly to the end walls of the casing to support a spring shade roller 13, having a shade 14 wrapped thereabout. The free end of the shade is reinforced with a metal strip 15 having a ring 16 at each end. 65

It will be noted that the free end of the shade may extend through the opening 11 of the casing and be pulled out to any distance desired. Mounted exteriorly of the casing and upon the ends thereof are a pair of hinge plates 17 and 18, the latter being somewhat longer than the other. Hingedly connected to each plate is a guide rod indicated at 19 and 20.

The upper portion of the casing is extended beyond the diametrical side as shown at 21, and hingedly connected to the longitudinal edge thereof is a clamping plate 22, springs 23 being provided to urge said clamping plate toward the casing. 75 80

In use, the device is placed upon the upper edge of the windshield of a motor vehicle, aeroplane, etc. The flat side of the casing bears against the rear side of the windshield, and the clamping plate 22 bears 85 against the front side of the windshield. The device is thus securely held against accidental dislodgment, but movement of the casing along the windshield is permitted, so that the shade may be properly positioned 90

to be interposed between the source of light against which the driver is to be protected, and his eyes. The shade may now be lowered to the distance required. It will be noted that the guide rods 19 and 20 depend from the 95 casing and enter the rings 16, and thus serve to hold the shade against flapping, when the device is not in use, or when it is to be stored or shipped, the shade is permitted to roll up upon the roller to the fullest extent. 100 The strip 15 partly entering the opening 11 of the casing. The ring 16 it will be noted rides up upon the hinge plates 17 and 18 as shown in Fig. 2. The guide rods 19 and 20 may now be folded up toward the casing 105 in overlapping relation, and sprung between a pair of resilient fingers 24 which are secured to the reinforcing strip 15 of the shade.

Thus it will be seen that with this device 110 the driver may protect his eyes against the early morning or evening sun, as well as

against artificial light by merely adjusting the shade or by moving the casing along the windshield.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention, what I claim as new and desire to secure by United States Letters Patent is:

1. A device of the character described including a casing, a shade roller mounted therein, a shade wrapped about the roller and having its free end extended through the casing, a pair of guide members hingedly mounted at the ends of the casing and adapted to depend therefrom, a reinforcing strip on the free end of the shade, rings on the ends of the strip to receive the guide members, said guide members being fold-

able in overlapping relation when the shade is retracted, and a spring clip on said reinforcing strip to receive the folded guide members.

2. A device of the character described including a casing, a shade roller mounted therein, a shade wrapped about the roller and adapted to be extended therefrom, hinge plates secured to the ends of the casing, guide members hingedly connected to said hinge plate, rings connected to the end of the shade adjacent the margins thereof and adapted to receive the guide members and to move therealong from one end of the guide member to the other, said guide members being foldable in overlapping relation when the shade is retracted, the rings in said position engaging around the ends of the hinge plate to permit folding movement of the guide members.

In testimony whereof I affix my signature in presence of two witnesses.

JOHAN H. E. THOMSEN. [L. s.]
